UNITED STATES PATENT OFFICE.

EDWARD H. MOTT, OF CHICAGO, ILLINOIS.

RAILWAY-CAR VENTILATION.

SPECIFICATION forming part of Letters Patent No. 254,148, dated February 28, 1882.

Application filed September 5, 1881. (No model.)

To all whom it may concern:

Be it known that I, EDWARD H. MOTT, of Chicago, in the county of Cook and State of Illinois, have invented certain new and useful 5 Improvements in Railway-Car Ventilators, of which the following, in connection with the accompanying drawings, is a specification.

In the drawings, Figure 1, Sheet 1, is a vertical central cross-section through the main 10 parts of my ventilating apparatus, and showing their relation to the car and one of the car-wheel axles. Fig. 2, Sheet 1, is a section in the plane of the line $x x$ of Fig. 1, viewed in the direction indicated by the arrow there 15 shown, and also showing a part of the same set out in detail. Fig. 3, Sheet 1, is a section in the plane of the line $x' x'$ of Fig. 2. Fig. 4, Sheet 2, is a section in the plane of the line y of Fig. 1, viewed in the direction indicated 20 by the arrow there shown. Figs. 5 and 6, Sheet 2, are details in perspective of the gate-shifting device; and Figs. 7 and 8, Sheet 2, are details in section and in perspective of one of the eduction-flues and of one arm of the 25 eduction-fan, respectively.

Like letters of reference indicate like parts.

My purpose is to provide improved means 30 for ventilating railway-cars; and my invention consists in certain features of construction relating to the ventilating mechanism or apparatus which I employ for that purpose, and hereinafter described and set forth as novel.

A represents the coach or body of a railway- 35 car, and B is one of the car-wheels. C is the wheel-axle, and D is a hollow metallic cylinder arranged and made rigid upon the wheel-axle. The purpose of this cylinder is to furnish a smooth and even bearing-surface for 40 the parts to be mounted upon it, as will hereinafter more fully appear.

D' is a vertical flange on the outer end of the cylinder D, and $a a$ are horizontal inwardly-projecting pins on the flange D'.

E is a sleeve on the cylinder D, and on which 45 it is capable of a laterally-sliding and rotary movement.

F is a vertical flange on the cylinder E, and $b b$ are small wings projecting outwardly from 50 the flange F. The cylinder E also has thereon the flanges $c c'$ and $d d'$, arranged as shown with relation to each other. Outside of the collars $d d'$ are loose rings $d'' d'''$.

G G are arms extending radially from the sleeve E, and G' G' are fans on the ends of the 55 said arms.

H is an annular chamber in which the fans G' G' play. The smaller circumferential portion of this chamber is open, as indicated at e , Fig. 1.

I is an air chamber or tube, forked to straddle the chamber H, as shown. The lower parts 60 of the forked portions or branches of the chamber I surround the axle C, and the walls of these lower parts are drawn in and fastened to the 65 rings $d'' d'''$ and to the edges of the smaller circumferential portion of the chamber H, respectively, as indicated at e' and e'' , Fig. 1. The chamber H and the tube I thus communicate with each other at e ; but in other respects these parts, except as hereinafter mentioned, are closed.

J and J' are ports in the chamber H.

K is a lever, and K' is a slot through which it passes.

L is a metallic box or lining in the slot K'.

M is a brace, to which the lever K is pivoted. The lower part of this lever is forked and knuckle-jointed to the upper part, as shown in 80 Figs. 1 and 4, and the arms of the forked part pass between the flanges c and c' . The arms of the forked part are represented at $f f'$ and the knuckle-joint at g . I make a knuckle-joint in this lever in order that it will not be materially affected by the varying motion of the 85 truck and coach.

It will be perceived on reference to Fig. 1 that if the handle of the lever K be moved in the direction indicated by the arrow there shown the sleeve E will be pushed toward the 90 flange D', and that the pins $a a$ will strike the wings $b b$ during the rotation of the axle C, and consequently rotate the sleeve and the fans connected thereto. In other words, while the parts mounted on the sleeve E move with it 95 the comparatively short distance it need be moved laterally to be engaged by the pins $a a$ during the rotation of the axle, so as to actuate the fans, this rotary movement is not communicated either to the box or chamber H or 100 to the tube or chamber I.

I may here state that, as the upper end of the tube I is to be connected to a system of air-tubes in and under the car, I make this connection by means of a flexible tube, I', I'' representing one of the air-tubes applied to the 105

body of the car and connected to the tube I' in the manner described.

In order that the lever K may be held or locked temporarily in any position in which it may be set, I apply to it one or more spring-catches, h h, or make the upper end of the lever itself slightly yielding, and in the edges of the box L, I make serrations or notches adapted to engage or receive the free springs h h, and so prevent any accidental displacement of the lever after it is set. It will only be necessary to press the springs h h out of the notches in which they rest in order to set the lever.

I arrange the tubes I' I'' in any suitable way. By preference I carry a main tube along the under side and central part of the floor of the car and fork this tube near the ends of the car. I also employ branch tubes suitably located, and the mouths of these branch tubes are arranged in those parts of the car to which the air therein is to be drawn for being ejected. At these places in the car I prefer to arrange ventilator registers or dampers N N, which may be regulated with facility by means of a thumb-wheel, N', extending a little way through the face of the register, as indicated in Fig. 7. It will now be perceived that if the fan be rotated in the direction indicated by the arrow shown in Fig. 2 the air will be sucked or drawn from the interior of the car into and through the registers, and thence through the air-pipes into the chambers I I and H, and expelled from the latter through the port J, it being understood that the port J' is then closed. The air drawn from the car will be replaced by other air entering either through the doors, windows, cracks, or ventilating openings. In other words, I draw the foul air out of the car, and fresh air is thus drawn in. By this means I am enabled to arrange the working parts of my apparatus underneath each car, and I expel the air there instead of there obtaining a supply and forcing it into the car.

It is obvious that a supply of air obtained underneath the car would be liable, for the most part of the time, to be filled with dust and dirt, and that air taken from the top and sides of the car would be liable to contain smoke and cinders. This would especially be the case with an apparatus there arranged, which would suck or draw in the air immediately about it.

By my method of ejecting the stale air from the car the fresh air enters through all the appliances with which the car may be provided for keeping out dust, cinders, and smoke. Besides these advantages, each car is provided with a complete and independent ventilating apparatus, and the rotating car-axle is the only motor or driving-power required for setting the working of the ventilating apparatus in action.

It will be perceived that if both ports J and J' should be left open the fans would be practically inoperative for the purpose for which they were intended, and that a current of air would be simply drawn into one port and ex-

pelled from the other, while possibly a small amount would be blown or forced into the car. It will also be perceived that if the car should be run in an opposite direction without being first turned around the direction of the rotary movement of the fans would be changed or reversed from that described, and that, the port J remaining open and the port J' being closed, the air would be sucked into the port J instead of being expelled therefrom. Consequently, when the direction of the car is changed the port before open should be closed and the one before shut should be opened. I have provided means for automatically performing the work of opening and closing the doors, and will now describe the same.

O is a slide having legs O' O' depending from two of the corners thereof, and P P' are valves or doors applied to the said legs, and so arranged as to open and close the ports J and J', in the manner hereinafter described.

Q is a rib on the slide O, and Q' is a rib on the upper side of the rib Q.

R is a rocking and yielding catch bar or lug applied to the side of the rib Q.

S S are bolts passing freely through the rib Q and rigidly attached to lug R.

T T are closed spiral springs on the bolts S S and between the rib Q and lug R. The lug is thus capable of a yielding movement to and from the rib Q, and one end of the lug may be pressed in toward the rib, while the other stands out therefrom.

V is a lateral recess in the lower part of one of the side walls of the chamber H. This recess lies in the arc of a circle having a center coincident with the axis on which the sleeve E turns. The slide O slides on the bottom of the recess V, and is correspondingly curved. The rib Q' enters a groove, f', in the top of the recess V.

V' is a short strap or bar crossing the recess V, and set in flush with the interior face of the wall of the chamber H, so as not to be in the way of the fans G' G'. This strap is so set or arranged as to press in the lug R when the slide O is moved back and forth in the recess V. When one end is so pressed in it will be out of the way of the fans; but the other will stand out into the chamber H far enough to be struck by them. When the fans move in such a direction as to strike the extreme end or end face of the projecting end of the lug R they will push the lug (and consequently the slide O and its attachments) along until the bar V' will draw in that end away from the fans and release the other end, and when the fans reach the end so released they will ride over it, as it is beveled for that purpose, as indicated at g', the lug being yielding, as described. This movement of the slide will be sufficient to close the port already open and open the one before closed. When the direction of the fans is again reversed the port first closed will be again closed and the one first open will be opened again. The fans cannot strike that end of the lug R which is nearest the port J', for

100

105

110

115

120

125

130

that end is then held in by the bar V', and the fans, in striking the other end of the lug, will ride over it in the manner and for the reasons already stated. When the direction of the 5 fans is reversed, however, the projecting end of the lug will be so struck as to carry the valve P to the port J and the valve P' away from the port J', and the end of the lug so released will be set to again shift the valves when the 10 direction of the fans is again changed. The air therefore will be drawn out of the car and discharged, either through the port J or the port J', in whatever direction the car may be moving, and when its movement is reversed 15 the valves P and P' will be set automatically in their proper positions.

It is to be understood that a valve-shifter may be employed on both sides of the chamber H, as indicated in Fig. 3.

20 It may be that the fans will have a tendency to blow some of the air past the exit-ports and keep it moving around in the chamber H without properly discharging it. To prevent this tendency I provide the valve-shifter with a bar, W, in which are the slots h' h'. I also make downwardly-inclined grooves h'' h'' in the interior faces of the walls of the chamber H. A' is a gate adapted to extend across the chamber H, and i i are pin-like extensions at 25 the corners of this gate. This gate I arrange across the chamber H at a point just above the port J when that port is open. By placing the upper pins, i i, in the grooves h'' h'' and the lower pins in the slots h' h' the position of 30 the gate A' will be such as will to a great extent prevent the air from being carried beyond the port J. When the valve-shifter is moved so as to close the port J the gate A' will be carried below that port and laid horizontally, 35 in which position the gate employed in connection with port J' is shown.

In order that cold air may be drained from 40 the car, registers may be placed in the floor and connected with exhaust-tubes leading to the chamber H.

The valve-shifting device and the gates may be employed also in combination with fans for blowing air into the cars.

I have not here attempted to describe many 50 of the minor details of constructing my ventilator apparatus, as they will occur to those familiar with the construction and operation of mechanism intended for analogous uses.

Although I have herein shown and described 55 the several features of my invention when employed in connection with car-ventilating apparatus, it is obvious that some of those features may be applied with advantage to other uses, and I do not therefore here intend to restrict myself to any particular use to which my improvements may be applied.

Having thus described my invention, what I claim as new, and desire to secure by Letters Patent, is—

65 1. The combination, in a car-ventilating apparatus, of a fan having a hollow axle, a rotat-

ing axle entering the said hollow axle, a fan-chamber surrounding the said hollow axle and fan, and having one or more ports, J J', and one or more ports or openings for communication 70 with an air-tube, substantially as specified.

2. The combination, in a car-ventilating apparatus, substantially as described, of a rotary fan, a fan-rotating axle, a fan-chamber having an induction and containing two ports, J and J', 75 and valves or doors for opening and closing the said ports.

3. The combination, substantially as described, in a car-ventilating apparatus, of a rotary fan, a fan-rotating axle, a fan-chamber 80 having an induction and containing two ports, J and J', the valves or doors P and P', and an automatic valve-shifting device for operating the said valve, as and for the purposes specified.

4. The combination, in railway-car-ventilating apparatus, of a fan adapted to be mounted on and rotated by the car-wheel axle, a fan-chamber communicating with an exhaust-tube and containing two exit-ports, and automatic 85 valve-shifting mechanism adapted to open first 90 one of the said ports and then the other upon the reverse rotation of the said fan, for the purposes set forth.

5. The combination, substantially as described, in a car-ventilating apparatus, of a 95 fan having a hollow axle, the rotating axle C, the fan-chamber H, and the air-tube I, surrounding the said hollow axle and entering the central part of the chamber H, the latter having therein one or more air-ports, J J', for 100 the purposes set forth.

6. The combination of the rotating axle C, carrying a clutch, D' a the sliding sleeve E, adapted to be engaged by the said clutch and carrying the fan G G', the fan-chamber H, having therein induction and exhalation ports, the air-tube I, entering the chamber H and connected to the said sleeve, and a lever for shifting the said sleeve in and out of engagement with the said clutch, substantially as and for 110 the purposes specified.

7. The combination, with a blower containing ports J J', of the slide O, carrying the valves or doors P P', the yielding rocking lug R, the rotating fan-shaft C, and the air pipes 115 or ducts of a car-ventilating apparatus, substantially as and for the purposes specified.

8. The gates A' A', one or more, arranged substantially as shown and described with relation to the exit-port of a blower containing 120 a fan mounted on an axle, C, for the purposes set forth.

9. The combination, in a car-ventilating apparatus, of a blower containing a fan mounted on an axle, C, the slots h'' h'', the ports J J', 125 the gates A' A', the slide O, the slotted bar W, and the yielding lug R, substantially as and for the purposes specified.

EDWARD H. MOTT.
